LIQUID FUEL BURNER

Filed Sept. 17, 1936

UNITED STATES PATENT OFFICE

2,108,918

LIQUID FUEL BURNER

William F. Falkenberg, Chicago, Ill.

Application September 17, 1936, Serial No. 101,218

2 Claims. (Cl. 158—77)

The invention relates generally to improvements in liquid fuel burners of the type shown and described in my co-pending application, Ser. No. 67,607, filed March 7, 1936, of which this application is a continuation-in-part, and more particularly to that type of a burner wherein crude oil or the like is forcibly discharged into a novelly constructed rotatable fuel atomizing nozzle so that the fuel is completely vaporized for free burning.

Some known types of liquid fuel burners having a rotating atomizing nozzle cannot satisfactorily utilize the heavier known grades of crude oil because of their inability to effect thorough atomization of the oil and complete mixing of air with the hydrocarbons therein, with the result that inefficient firing is effected with great loss of potential heat. The unburned carbon tends to cling to the burner nozzle and to the walls of the fire box thus necessitating frequent interruptions in service for cleaning.

Other known types of rotary liquid fuel burners can effect a more satisfactory mixing of the hydrocarbons and air only when the crude oil is pre-heated. However, these burners also are unsatisfactory also because they fail to produce a mixture for free burning. This is primarily because the air and fuel are not properly mixed in the burner to allow burning of the fuel at the nozzle. It burns at the extreme end of the stream only after the improper mixture has been violently agitated. This agitation takes place only when the mixture strikes the back wall of the fire box or a baffle therein. Obviously, the fuel is consumed as it rebounds from the wall or baffle with the result that a back pressure is created in the fire box and "puffing" of the burner results. Accordingly either type of burner is expensive to operate, inefficient in results obtained and in many instances wholly unsuited for certain specific installations. These and other known disadvantages in the use of known types of burners for burning the heavier grades of crude oil are all overcome satisfactorily, efficiently and inexpensively by the construction disclosed herein.

It is therefore, an object of the invention to provide a liquid fuel burner with an improved rotatable fuel atomizing nozzle having a plurality of circumferentially inclined passageways through which partly atomized fuel is entrained.

Another object is to provide a liquid fuel burner with means to effect complete mixing of air with the hydrocarbons and thereby deliver a free burning highly atomized fuel mixture at the discharge end of the burner.

Another object is to provide a fuel atomizing nozzle with improved means to reduce liquid fuel to extremely fine particles prior to its being entrained into the discharge end of said nozzle.

Another object is to provide a fuel atomizing nozzle with means to prevent formation of a film of fuel on the inner surface of the receiving end of said nozzle.

Another object is to provide a rotatable fuel atomizing nozzle and shaft with novel means to efficiently reduce the liquid fuel to a highly atomized volatile substance and discharge said substance substantially uniformly.

Another object is to provide an improved fuel atomizing nozzle which is positive in operation, inexpensive to construct and highly efficient.

The foregoing and such other objects of the invention as will appear hereinafter as the description proceeds will be more readily understood from a perusal of the following specification, reference being had to the accompanying drawing, in which:

Fig. 1 is a vertical central sectional view, partly broken away, through a liquid fuel burner embodying features of the invention, showing parts in elevation.

Fig. 2 is an enlarged longitudinal sectional view through the improved fuel atomizing nozzle showing associated parts in elevation.

Fig. 3 is an elevational view of the discharge end of the nozzle shown in Fig. 2.

Fig. 4 is a transverse sectional view taken on line 4—4 of Fig. 2.

Fig. 5 is a view similar to Fig. 2, showing a modified form of construction.

Fig. 6 is a sectional view of the fuel atomizing nozzle taken substantially on line 6—6 of Fig. 5.

As best shown in Fig. 1, the liquid fuel burner preferably is of the type shown in my aforementioned co-pending application, and preferably includes a cylindrical casing 11 having a dished end wall 13 which terminates in an annular flange 14 of reduced diameter. A substantially conical plate 15 is secured over the open face of the cylindrical casing 11 to provide a wall having a central opening 16 in axial alignment with the annular flange 14. An air nozzle 17, which tapers towards its free open end, is fitted over the flange 14 as shown, and is adapted to extend into a similarly tapered flanged inlet opening 18 in a fire door cover plate 19 on boiler 21. The burner casing 11 may be held in an inclined position against the cover plate 19 in any practical manner but preferably is hinged thereto so that it may readily be moved into its operating position, as shown in Fig. 1, or swung outwardly clear of the opening 18. A flanged collar 22 preferably is fitted over the enlarged end of the air nozzle 17 to close the annular opening between said nozzle and the flanged opening 18, if desired.

A motor 23, mounted in axial alignment with the cylindrical casing 11, has a driven shaft 24 extending toward said casing carrying an ex-

tension 25, the diameter of which preferably is successively reduced to provide a bearing portion 26, an extension 27 and a threaded end 28. The bearing portion 26 is journaled in a suitable bearing block 29, preferably mounted on the wall 13 of the casing as shown. Mounted within the casing 11 upon the large diameter of the shaft extension 25 is an air fan 31, which may be of any type suitable for creating a uniform forced draft 10 through the central opening 16 and out through the air nozzle 17. The direct flow of air through the casing 11 may be aided materially by providing a suitable dished baffle 32 spaced from the wall 13 of the casing.

15 A fuel atomizing nozzle 33 is securely mounted upon the threaded end 28 of shaft extension 25 and extends into and preferably a short distance beyond the reduced open end of air nozzle 17. As best shown in Figs. 2, 3 and 4, the fuel atomizing nozzle 33, which is in the form of a cylindrical body, preferably includes a fuel discharge cup portion having a uniform outside circumferential surface and an internal coned fuel discharge surface 34 which tapers outwardly circumferentially 20 towards the free open end thereof. The relatively thick wall 35 of the cup portion is centrally apertured to receive the shaft end 28 and has a plurality of circumferentially spaced passageways 36 therein.

25 As best shown in Figs. 3 and 4, the passageways 36 are inclined circumferentially in a direction opposite to the direction of rotation of the fuel atomizing nozzle (as indicated by the arrows) for a purpose to be more fully described later.

30 An annular flange 37 extends from the wall 35 of said cup portion outwardly around but spaced from a portion of the shaft extension 27, to provide a fuel receiving chamber 38. Crude oil or other liquid fuel is delivered into the chamber 38 35 through a pipe line 39 which has its discharge outlet positioned directly above the embraced shaft 27 whereby all fuel discharged is deposited onto said rotating shaft. The embraced shaft portion 27 preferably is serrated longitudinally, 40 as at 41, or otherwise roughened to prevent the fuel from flowing down one side or the other thereof during its rotation. Obviously, the serrations 41 on the rotatable shaft cause the fuel deposited thereon to be thrown violently radially 45 against the inner surface of flange 37. While this violent agitation of the fuel is being effected, air under pressure is flowing through the fuel receiving chamber 38 and passageways 36 into the coned fuel discharge portion of the nozzle, and the finer 50 particles of said fuel are entrained thereby through the passageways 36. The heavier fuel particles however strike the inner surface of the receiving chamber 38 and are further broken up. Some of the fuel, however, tends to adhere to said 55 inner surface in the form of a film.

Formation of such a film of fuel is positively 60 prevented by providing grooves 42 on the inner surface of the flange. The grooves 42 also are inclined circumferentially parallel with and one in axial alignment with each passageway 36. The fuel, instead of adhering to the inner surface of the flange is carried into the grooves 42 and entrained through the passageways 36 into the coned discharge portion of the cup and is discharged therefrom substantially radially into the path of air flowing through the annular passage 43 between the outside of the fuel atomizing nozzle 33 and the inside of the air nozzle 17.

It is apparent that the violent agitation and

breaking up of the liquid fuel in the receiving chamber carries said fuel into the path of the air stream prior to and after it is discharged from the atomizing cup and effects complete mixing of the air and hydrocarbon to provide a highly volatile free burning substance which burns close to the nozzle. 5

In the fuel atomizing nozzle shown in Figs. 5 and 6 and also shown in my said co-pending application, the air passageways 36^a are spaced 10 inwardly from the inner surface of the nozzle cup and also are inclined circumferentially in a direction opposed to the direction of rotation of said nozzle. The rearwardly extending flange portion 37^a however, has an internal annular 15 flange 44 adjacent its free edge and is inclined on its inner surface outwardly toward the bottom of the cup. Liquid fuel deposited therein through the fuel pipe line 39 is deposited, as before, upon the rotating serrated shaft portion 27 and is 20 prevented from dripping or flowing over the edge of the receiving chamber by the internal annular flange 44. The free edge of the coned discharge chamber preferably is flared outwardly sharply, as at 45, and the internal edge portion 25 of the air nozzle 17^a is chamfered, as at 46, to insure wide radial distribution of the atomized liquid fuel. This form of discharge is particularly advantageous when the burner is installed 30 in a furnace having a relatively short fire box. 30

Although exemplary forms of the improved structures have been described herein in detail it is to be understood that the detail structure of the liquid fuel atomizing nozzle and the type of burner in which it is installed may vary to 35 suit various manufacturing or installation requirements without departing from the spirit of the invention or the scope of the appended claims.

I claim:

1. A liquid fuel burner including an air nozzle and a rotatable shaft extending therein, a fuel atomizing nozzle mounted axially within said air nozzle on said shaft, said fuel nozzle comprising a cup having an internal coned fuel discharge surface and an end wall, a flange extending outwardly from said wall around but spaced from said shaft to provide a fuel receiving chamber, means feeding fuel to said receiving chamber, said wall having a plurality of inclined passageways extending therethrough, and the surrounded shaft portion and the inner surface of said flange each having serrations therein to reduce the fuel to fine particles prior to its being carried through said passageways into said cup. 55

2. A liquid fuel burner comprising, in combination with a blower casing and a rotary fan therein, an open ended discharge nozzle at the discharge end of said casing, a substantially tubular fuel atomizing nozzle mounted within said 60 discharge nozzle for rotation with the fan, a wall in said fuel nozzle dividing said nozzle into a fuel receiving chamber and a fuel discharge chamber and having a plurality of circumferentially spaced angularly disposed parallel passageways therein, said passageways being adapted to admit fuel from the receiving chamber into the discharge chamber, the circumferential wall of said receiving chamber being provided with shallow angularly disposed grooves, said grooves 65 communicating with the passageways, and means feeding fuel to the receiving chamber. 70
